US0D1009311S

(12) **United States Design Patent** (10) **Patent No.:** **US D1,009,311 S**
(45) **Date of Patent:** **** Dec. 26, 2023**

(54) **LIGHT-EMITTING DEVICE**

(71) Applicant: **DONGGUAN XINGYANG TECHNOLOGY CO., LTD.**,
Dongguan (CN)

(72) Inventor: **Weixing Chen**, Dongguan (CN)

(73) Assignee: **DONGGUAN XINGYANG TECHNOLOGY CO., LTD.**,
Dongguan (CN)

(**) Term: **15 Years**

(21) Appl. No.: **29/827,220**

(22) Filed: **Feb. 18, 2022**

(51) LOC (14) Cl. **26-04**

(52) U.S. Cl. **D26/1**
USPC **D26/1**

(57) **CLAIM**

The ornamental design for a light-emitting device, as shown and described.

DESCRIPTION

FIG. 1 is a perspective view of a first embodiment of a light-emitting device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2;

FIG. 10 is a perspective view of a second embodiment of the light-emitting device;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is an enlarged view of portion 18 shown in FIG. 11.

The dash-dash broken lines in the drawings depict portions of the light-emitting device that form no part of the claimed design. The dot-dash broken lines represent boundaries of the enlarged portions and form no part of the claimed design.

1 Claim, 18 Drawing Sheets
